UNITED STATES PATENT OFFICE

ALBERT HAYES, OF SALT LAKE CITY, UTAH.

SOUND-BOX.

1,061,071.

Specification of Letters Patent.

Patented May 6, 1913.

Application filed March 8, 1913. Serial No. 752,886.

To all whom it may concern:

Be it known that I, ALBERT HAYES, a citizen of the United States, residing at Salt Lake City, in the county of Salt Lake, State 5 of Utah, have invented certain new and useful Improvements in Sound-Boxes, of which the following is a description, reference being had to the accompanying drawings, forming a part hereof.

10 My invention relates to sound boxes for gramophone and graphophone reproducers and has for its object to provide a sound box which will produce improved results in the reproduction of sound from a record 15 disk or cylinder or other means for causing vibration of a diaphragm particularly increased loudness, greater clearness, greater sweetness of tone, the production of throat notes as against the nasal tones characteristic of most sound reproducers in use, and 20 the elimination of overtones.

With these objects in view my invention consists in the construction and combination of elements hereinafter described and 25 claimed.

Referring to the drawings, Figure 1 is a central vertical sectional view of a sound box embodying my invention on the plane of the lever by which the diaphragm is vibrated. Fig. 2 is a central vertical sectional view on a plane at right angles to that on which Fig. 1 is taken, and Fig. 3 is a bottom plan view of the sounding board and the ring which carries it.

30 In the drawings 1 indicates the body of the sound box having central opening 2 in which is received the end of the horn or sound tube (not shown). This body 1 has at its periphery a flange 3. Within the 35 chamber formed by the flange 3 concentric with the opening 2 is a ring 4 the face of which is dressed off and is throughout in the same plane which plane is at right angles with the axis of the body 1. Between the ring 4 and the flange 3 is a depressed annular channel 5 which is so formed that it is deeper, relative to the plane of the face of the ring 4, on one side than on the other so that the plane of the 40 bottom of the annular channel 5 is at a slight angle to the plane of the dressed face of ring 4. On one side the flange 3 is cut away and is provided at the ends of the cut away portion with lugs 6 each of which is 45 provided with an inwardly extending bear-

ing point 7, preferably adjustable in the lugs, to form the bearings for the trunnions of a lever 9, the outer arm 10 of which is provided with a socket to receive the needle or stylus (not shown) a set screw 11 being 60 provided for holding the needle in position. The inner arm 12 of lever 9 extends into line with the center of the opening 2 and at its inner end is bent toward said opening as shown at 13. To the inner end of the arm 13 is rigidly secured a disk 14, preferably of mica of a diameter slightly less than the interior diameter of the flange 3, and provided on its periphery with a ring 15 of compressible material such as semi-hard 70 rubber, that is rubber which has been vulcanized sufficiently to make it harder than soft rubber but not sufficiently to give it the rigidity of hard rubber. This ring 15 envelopes the periphery of the disk so as to 75 form a somewhat compressible ring above it and below it.

16 indicates what may be termed a sounding board. This is carried by a ring 17 having inwardly extending annular shoulder 18 adapted to fit over and upon the ring 15 to force it downward so that the portion of the ring below the periphery of the disk 14 will be pressed firmly against the bottom of the annular channel 5 throughout its extent 80 so that the disk 14 will be forced or distorted into a plane oblique to, that is not at right angles to, the axis of the sound box. The sounding board 16 is provided with openings 20 preferably curved as shown, and within the sound box are arranged strings 21 preferably of cat-gut having their ends secured in openings formed in the ring 17, the strings being drawn taut and being each arranged near to one of the openings 20 85 and in the same general direction as that of the opening. By the use of the sounding board 16 with its openings and the strings 20 overtones are eliminated so that the tones produced from the record are pure and clear. 90

By reason of the bowing or distortion of the disk 14 as above described it is much more sensitive than it would otherwise be. Its edges are firmly held and the only movement permitted is a movement of the central portion of the disk and this movement is restricted by the distortion.

The portion of the compressible ring 15 which is beneath the periphery of the diaphragm is restricted by the outer edge of 110

ring 4 on the one side and the flange 3 on the other side from expanding laterally when put under compression.

It will, of course, be understood that I do not desire to be limited to the particular construction and arrangement shown as it will be obvious that the precise construction and arrangement may be varied without departing from the spirit of the invention.

10 Having thus described my invention what I claim is:

In a sound box the combination with a box body having a central opening therein, a diaphragm within the box body and 15 means for vibrating it, of a sound board ex-

tending over and closing the box body, having openings therein, and strings under tension extending across the sound box between the sounding board and the diaphragm, the sound board and strings being 20 arranged on the side of the diaphragm opposite to that which faces the central opening in the sound box body.

This specification signed and witnessed this 8th day of March A. D. 1913.

ALBERT HAYES.
